UNITED STATES PATENT OFFICE.

JAMES CALLAN, OF WATERBURY, CONNECTICUT, ASSIGNOR TO HOLMES, BOOTH & HAYDENS, OF NEW YORK, N. Y.

METAL TUBE.

SPECIFICATION forming part of Letters Patent No. 388,824, dated September 4, 1888.

Application filed June 12, 1888. Serial No. 276,871. (No model.)

To all whom it may concern:

Be it known that I, JAMES CALLAN, of Waterbury, in the county of New Haven and State of Connecticut, have invented a certain 5 new and useful Improvement in Tubing, of which the following is a specification.

The improvement relates particularly to tubing of that kind which has two ducts or compartments.

- 10 I will describe tubing embodying my improvement and then point out the various novel features in the claims.

In the accompanying drawings, Figure 1 is an end view of a section of tubing embodying 15 my improvement. Fig. 2 is a side view of the section illustrated in Fig. 1. Fig. 3 is an end view of the other section thereof. Fig. 4 is an end view of the two sections fitted together, and Fig. 5 is an end view of the completed 20 tubing.

Similar letters of reference designate corresponding parts in all the figures.

A designates a semi-cylindric tube section made in any suitable manner. It may be 25 made by taking a strip of sheet metal, such as brass, drawing it up by means of dies or other appliances, and uniting the edges of the strip by brazing, soldering, or other means. Preferably the edges will be joined on the flat portion; but they may be joined on the curved portion, or at the junction of the curved portion with the flat portion. This tube section 30 may be solid, drawn so as to be without joint, if desirable. This tube section A is so formed 35 as that it will be provided at the junction of the circular portion and the flat portion with lips or flanges a' a''. These lips or flanges will extend throughout the length of the tube section.

40 B designates a strip of metal, which will preferably be the same metal as that of which the tube-section A is made. This strip B is bent transversely, so as to be arc-shaped in the transverse section, which forms another tube section. The tube-section B is fitted into the 45 recess formed between the lips or flanges a' a'' of the tube-section A. Owing to the lips

or flanges, the two tube-sections may be more easily joined than otherwise, and the spaces or grooves formed by the extension of the flanges 50 or lips a' a'' slightly beyond the edges of the tube-section B form convenient receptacles for solder employed to unite the tube-sections. After the tube-sections have been united, as described, the tubing thus formed will preferably be pressed on the two edges and subjected 55 to dies or other appliances for perfecting its contour.

The tubing may be cylindrical or of other shape. 60

The tubing thus made will be simple and cheap, and will have two ducts or compartments, one of which may be employed for gas in a chandelier and the other for electric-lamp wires in such chandelier. The danger of leak- 65 age from one duct or compartment into the other will be extremely small and may be absolutely avoided if the joint between the edges of the strip forming the tube-section A is made at the curved portion of this tube-section. 70

What I claim as my invention, and desire to secure by Letters Patent, is—

1. As a new article of manufacture, tubing formed of two tube-sections, one of which is made of a strip bent so as to have a curved 75 portion and a flat portion, and the other of which is made of a strip bent into arc shape and fitted and secured against the flat portion of the first-mentioned tube-section, substantially as specified. 80

2. As a new article of manufacture, tubing composed of two tube-sections, one of which is made of a strip of metal bent to form a curved portion, a flat portion, and lips or flanges extending from the junctions of these two portions, and the other of which is made of a strip of metal bent to arc shape fitted and secured with its edges against the lips or flanges of the first-mentioned tube section, substantially as specified. 85

JAMES CALLAN.
